(57) **CLAIM**

The ornamental design for a child supporting apparatus for attachment to a shopping cart, as shown and described.

DESCRIPTION

FIG. 1 is a perspective view of a child supporting apparatus coupled with a large shopping cart according to our new design;

FIG. 2 is a side view thereof;

FIG. 3 is a front view thereof;

FIG. 4 is a bottom plan view thereof;

FIG. 5 is a top plan view thereof;

FIG. 6 is a perspective view of the child supporting apparatus coupled with a medium shopping cart, according to our new design;

FIG. 7 is a side view thereof;

FIG. 8 is a front view thereof;

FIG. 9 is a bottom plan view thereof; and,

FIG. 10 is a top plan view thereof.
